KNITTED FABRIC

Edwin Wildt, Henry Harold Holmes, and John Cyril Herbert Hurd, Leicester, England, assignors to Wildt and Company Limited, Leicester, England, a company of Great Britain

Application April 2, 1943, Serial No. 481,608
In Great Britain March 16, 1942

2 Claims. (Cl. 66—201)

1

This invention relates to improvements in knitted fabric, the object of the invention being to produce a patterned fabric with novel characteristics of an attractive appearance adapted for use for a variety of purposes, but especially for articles of clothing as will be hereinafter described.

In its broadest aspect, the invention comprises a patterned knitted fabric wherein the pattern is constituted by a fancy stitch combination consisting of a lap or wrap or embroidery loop or stitch effect and a transferred loop or stitch effect directly associated.

Effects thus produced are for brevity herein-after referred to in the following description and in the appended claims as the "characteristic novel effects."

The essential novel and distinguishing feature of the present invention is that the lap or wrap or embroidery loop or stitch effect and the transferred loop or stitch effect are contained in the same needle wale, or needle wales, as the case may be, of the fabric, in contradistinction to being contained respectively in different needle wales.

This direct association of lap or wrap or embroidery loops or stitches and transferred loops or stitches results in the production of a fabric which possesses attractive ornamental and cellular characteristics.

In the preferred embodiment of the invention the lap or wrap or embroidery loops or stitches and the transferred loops or stitches are interconnected or knitted together.

The invention includes as a characteristic feature a patterned knitted fabric wherein the patterned effect is constituted by lap or wrap loops or stitches and pelerine stitches directly associated, e. g. interconnected or knitted together.

The pattern may be composed of individual characteristic novel effects distributed over the ground fabric, or of such effects formed either in substantially continuous or interrupted manner walewise or/and coursewise so that the said effects are present either throughout the fabric, or only in predetermined portions or areas thereof in the form of stripes, panels, blocks, diamonds or other figures or any desired combination thereof, according to requirements.

The transferred loops or stitches may be directly associated with the lap or wrap or embroidery loops or stitches suchwise that the cellular effects are contained within the lap or wrap or embroidery effects.

The characteristic novel effects may be con-

2

tained in single needle wales each including loops or stitches composed of an embroidery thread or threads, and stitches or loops of ground or main yarn transferred from another wale, e. g. a sinker wale, to the left only, or to the right only, or to both the left and the right, alternately, or in any other desired order. Alternatively, the said effects may be contained in two or more successive needle wales with lap or wrap or embroidery loops or stitches in the respective wales composed of separate threads, or of the same thread as in multi-wale lap or wrap effects, and loops or stitches of the ground or main yarn transferred to adjoining needle wales from an appropriate intermediate wale by being spread laterally in opposite directions.

Thus, in a fabric wherein the characteristic novel effects consist of combined lap or wrap or embroidery loops or stitches and pelerine stitches, the sinker loops forming the pelerine stitches may be transferred either to a needle wale on the left of the sinker wale, or to a needle wale on the right of the sinker wale, or to the left and the right, alternately, or in any other desired order, or such loops may be spread laterally to left and right so as to be incorporated in the needle wale, or adjoining needle wales, with the lap or wrap or embroidery loops or stitches.

The fabric may contain a combination of any 30 two or more of the aforesaid needle wale formations in any desired sequence.

The said effects may include either single transferred loops or stitches or an accumulation of two or more of such loops or stitches.

While in order to produce distinct patterns on the face of the fabric the characteristic novel effect would be constituted by combined lap or wrap or embroidery stitches and transferred loops or stitches, it is within the scope of the invention to provide a fabric wherein the characteristic novel effects include, in contradistinction to stitches, loops of embroidery thread associated with transferred loops or stitches, the former being interconnected with loops of the ground fabric so as to appear distinctly at the back of the fabric, thereby forming a pattern or design effect useful in the event of it being desired to show the reverse or inside of the fabric. The pattern or design effect thus produced may also appear less distinctly on the face of the fabric. If desired, the fabric may include characteristic novel effects of both forms so that there will be both distinct pattern or design effects and subdued pattern or design effects on the face of the

55 fabric.

As regards the lap or wrap or embroidery effects, when these are interrupted in a walewise direction loose portions or floats of the embroidery thread or threads occur on the back or inside of the fabric between adjacent patterned portions. In some instances the presence of such loose portions or floats may be objectionable.

Accordingly, in fabric wherein the pattern is interrupted as aforesaid, the embroidery thread or threads may also be interconnected with loops of the ground fabric between the spaced patterned portions. This interconnection may be continuous, i. e. course by course, or at short intervals, e. g. of one or two courses, so that loose portions or floats are entirely avoided or are considerably shortened and an additional pattern effect is produced distinctly on the back or inside of the fabric which may appear in corresponding but subdued form on the face of the fabric as hereinbefore described with respect to the characteristic novel effects but of course without transferred loop or stitch effect.

The characteristic novel effects may be produced in conjunction with ground fabric composed of one of the primary stitch formations, plain, ribbed or purl, or any desired conventional variation thereof, such as tuck or miss stitch effects, or of any two or more of these in combination, in order to enhance the appearance of the fabric.

For example, the invention may be carried into practice in simple plain knitted fabric, or in purl knitted fabric with the characteristic novel effects produced in the plain stitch portions of the purl knitted fabric.

Alternatively, the fabric may include courses composed partly of purl stitches and partly of plain stitches, with the said effects produced in the plain stitch portions.

Thus in one embodiment of the invention the characteristic novel effects may be produced in areas composed of plain stitches interspersed with areas composed of purl stitches, and the said areas may form solid or hollow figures, stripes, panels, bands or the like, or any desired combination thereof, or may form other broken designs or patterns. If desired, the fabric may include so-called jacquard, e. g. purl, designs in association with the characteristic novel effects.

As will be understood, many and diverse effects or different combinations of the kind aforesaid may be obtained by appropriate production of desired conventional stitch formations and the characteristic novel effects in desired wales and courses of the knitted fabric. The attractiveness of the fabric may be enhanced by yarn colour change, the use of which is well understood in the art.

In order that the invention may be more clearly understood and readily carried into practical effect, two examples of the improved knitted fabric will now be described with reference to the accompanying drawings, wherein,

Figure 1 is a structure diagram, drawn to a greatly enlarged scale, illustrating the front face of a portion of fabric incorporating one form of the improved fancy stitch combination, and

Figure 2 is a similar view depicting a modification hereinafter to be described.

Like parts are designated by similar reference characters throughout the drawings.

The portion of fabric represented in Figure 1 consists of a structure of purl stitches p and plain stitches ps , and is shown as it leaves the needles of the machine upon which it is pro-

duced. The spaced needle wales are indicated at nw , while the intervening sinker wales are designated sw . The characteristic novel effects in this example combine to produce in the fabric a clear opening O which is defined or emphasized by reason of it being surrounded by embroidery stitches. This cellular effect is constituted by wrap or embroidery stitches es and transferred loops tl , directly associated. Two of

the embroidery stitches, es^1 , viz. one in each of two adjoining needle wales nw , are knitted together with the transferred loops tl . The latter form pelerine stitches, and are produced by the transference laterally in opposite directions of an accumulation of sinker wale loops from three successive courses C, D and E suchwise that said loops become meshed with knitted loops ps^1 in the next course F. The pelerine stitches are produced by the use of a pair of transfer instruments working together. The fabric is knitted from a single main yarn y which, for convenience in illustration, is left unshaded. On the other hand, the continuous wrap or embroidery threads t from which the embroidery stitches are formed is shaded for emphasis. As will be appreciated from a consideration of Figure 1, the transferred loops tl , i. e. the pelerine stitches, are directly associated with the wrap or embroidery stitches suchwise that the cellular effect O is contained within the wrap or embroidery effects.

This is achieved by reason of the fact that in each of the two needle wales concerned the transferred loops tl are knitted together with a rap or embroidery stitch es^1 preceded walewise by four

other wrap or embroidery stitches es respectively in the courses A, B, C and D. The pattern effect just described is therefore contained in two successive needle wales nw with wrap or embroidery stitches es^1 in the respective wales composed

of separate threads t and stitches tl of the ground or main yarn y transferred to these needle wales from the intervening sinker wale sw by being spread laterally in opposite directions as aforesaid. Wherever an embroidery thread is formed

into a stitch, it is, of course, knitted in plating relation with the main yarn. In this example loose portions or floats f of the embroidery threads t occur on the back or inside of the fabric. It is these floats which, when they extend

between one cellular effect and another, might in some instances be objectionable as hereinbefore alluded to. In these instances it is preferred that the embroidery threads t shall be interconnected with loops of the ground fabric between the spaced cellular effects in the manner hereinafter to be described with reference to Figure 2.

In the example illustrated in Figure 2, each of the two embroidery threads t is continuously interconnected course by course with loops ps of the ground fabric. Thus, instead of being formed into stitches at opposite sides of the opening O , loops el of embroidery thread are associated with the transferred loops tl . As will be seen, these loops are so interconnected with the ground fabric as to appear distinctly at the back of the latter, thereby forming a pattern or design effect useful in the event of it being desired to show the reverse or inside of the fabric. This pattern or design effect appears less distinctly on the face of the fabric. By reason of the threads t being continuously interconnected course by course with the loops ps , loose portions or floats such as those designated f in Figure 1 are entirely avoided.

The invention is applicable to knitted fabric, flat or tubular, knitted in the piece, i. e. in a continuous manner, intended to be cut up subsequently for manufacture into garments such as pullovers, slipovers, jumpers, jackets and like outerwear, and to lengths of fabric knitted in string formation and joined by separating or parting courses or/and draw threads so as to enable them to be readily separated, as well as to knitted articles, such as stockings, half-hose, socks or the like, knitted separately, or produced in string formation with separating or parting courses or/and draw threads as and for the purpose aforesaid. Accordingly, the expression "knitted fabric" is to be regarded as including garment lengths or articles as well as fabric knitted in a continuous manner.

The invention is also to be regarded as including knitted fabric of the patterned or fancy character hereinbefore set forth comprising a welt, a rib knitted course, or courses such as may form the ribbed waist band of a slipover, pull-over or jumper or the ribbed top of a stocking, half-hose or sock, and a main portion with desired conventional stitch effects and the characteristic novel effects as aforesaid, produced in longitudinal sequence. In this connection the rib knitted course or courses may be of ordinary rib, such as 1/1 or 2/2 combination, or when there are several courses the ribbed portion produced may be of any desired fancy character. When such fabric is produced in the form of garment lengths or articles in string formation

with repetition of the sequence aforesaid, and with a separating or parting course or draw thread between the welt of one length or article and the main portion of the next, a finished edge is produced at one end of each garment length or article when the said lengths or articles are separated by removal of the separating or parting courses or the draw threads.

What we claim then is:

- 10 1. Knitted fabric comprising a structure composed of purl stitches and plain stitches knitted from a ground yard, and separate threads knitted into wrap effects in at least two successive needle wales of said structure, loops of the ground yarn being spread laterally in opposite directions and thereby transferred to said adjoining needle loops from an appropriate intermediate wale where they are interlooped with the combined adjoining loops and the wrap effects.
- 15 2. Knitted fabric comprising a structure composed of purl stitches and plain stitches knitted from a ground yarn, and separate threads which are knitted into wrap effects in plain stitches of two successive needle wales of said structure, sinker loops from the intermediate sinker wale being spread laterally to left and right and incorporated in the said adjoining plain stitches where they are knitted together with the combined adjoining plain stitches and the wrap effects.
